UNITED STATES PATENT OFFICE.

ALBERT WEBER, OF UNION, NEW YORK.

FOLDING UMBRELLA.

1,068,376.

Specification of Letters Patent.

Patented July 22, 1913.

Application filed December 6, 1910. Serial No. 595,908.

To all whom it may concern:

Be it known that I, ALBERT WEBER, a citizen of the United States, residing at Union, in the county of Broome and State of New York, have invented new and useful Improvements in Folding Umbrellas, of which the following is a specification.

This invention relates to folding umbrellas, and the object of the invention is 10 to provide an umbrella frame which may be easily and quickly collapsed in order that the same may be folded into a small bundle and whereby the umbrella may be carried in the pocket of the owner or packed within 15 in a trunk or satchel when desired.

With the above and other objects in view which will appear as the description progresses, the invention resides in the novel construction and arrangement of parts here- 20 inafter fully described and claimed.

In the accompanying drawings, Figure 1 is a vertical longitudinal sectional view showing the device in its raised position. Fig. 2 is a similar view illustrating the de- 25 vice in its collapsed or folded position. Fig. 3 is a detail sectional view of the slide. Fig. 4 is a similar view of the portion of one of the sectional brace members. Fig. 5 is a similar view of the joint connecting the sec- 30 tional ribs. Fig. 6 is a plan view of the blank from which the joint is struck. Fig. 7 is a perspective view of the hinge member connecting the inner rib section with the outer brace section.

35 It is to be understood that the cover of the umbrella is secured to the frame in the ordinary manner, the cover, being of flexible material, does not interfere with the operation of any of the parts. It is omitted 40 from the drawing in order that the framework, to which the invention appertains, may be more clearly illustrated.

In the accompanying drawings, the num- 45 meral 1 designates the staff of the umbrella. The staff 1 is formed of a plurality of tu- 50 bular members, and in the showing illus- trated in the drawing the said staff com- 55 prises an upper section 2 which is slidably mounted in a second section 3, while con- 60 nected with the lower extremity of the said section 3 is a hollow handle 4. The lower portion of the member 3 is offset or provided with an annular rib 5, while directly above the said rib the section is threaded as at 6. 65 The handle 4 is formed with an offset shoulder 7, the latter adapted to engage

with the rib 5 of the section 3, and the hollow handle is formed with threads 8 above the said shoulder 7, the threads adapt- 60 ed to coact with the threads 6 of the mem- ber 3. By this arrangement it will be noted that upon grasping the member 3 and ro- 65 tating the handle 4, so as to bring its threads out of engagement with the threads of the member 3, the said member may be easily 70 and quickly telescoped within the hollow handle 4. The lower extremity of the upper staff section 2 is formed with an annular rib 9 and the said rib is adapted to coact with the shoulder 10 formed adjacent the 75 upper extremity of the staff section 3. The hollow section 2 is formed upon its opposite faces and at a proper distance from each other with suitable openings 11 and 12. Both of these openings are adapted to re- 80 ceive the outwardly projecting portions of spring catches 13 and 14. The catch 13 is adapted to engage with the upper end of the section 3 when the sectional staff is in its spread position as illustrated in Fig. 1 85 of the drawings. The spring catch 14 is adapted to sustain the slide of the device in a manner which will presently be set forth.

Integrally formed upon or otherwise connected with the open top of the staff sec- 90 tion 2 is the top notch 15 of the device. Pivotally secured within the spaced de- 95 pressions provided by the notch are the inner rib sections 16 of the cover support. These rib sections are of the ordinary formation and are provided, adjacent their extremities with the joints 17. These joints 17 are constructed of a single piece of flattened ma- 100 terial and are bent to have their body por- tions of a substantially cross sectional U- 105 shape. The said extremities of the connect- ing portions of the U-shaped bodies are cut away as designated by the numerals 18 and pivotally connected to the sides of the joints between the said cut away portions 18 and 110 opposite the pivotal connection of the said joints with the members 16, are the outer rib sections 19.

It will be noted that the top or connecting portion of the joints 17 is arranged so that the downwardly extending portions of each of the rib sections will contact the same, when the umbrella is in its open position as illustrated in Fig. 1 of the drawings, and that the side walls contacting the sides of 110 the said ribs will be tightly engaged by the sides of the said joints, and thus producing

a strong and effective jointure of the sections 16 and 19. It will be further noted that the cut-away portions 18 of the connecting member provide U-shaped slots, the inner edges of which are adapted to engage the rib sections 16 and 19 when folded so as to hold said sections in proper spaced relation.

Mounted upon the staff, is a slide 20. This slide 20 is constructed of resilient material and comprises a substantially ellipsoid formation, the same being formed with a plurality of longitudinally extending slits extending toward the enlarged center thereof from each of its reduced ends. The said reduced ends are each formed with a flaring mouth 21, so that the said slide may readily pass from one of the staff sections to the other and to tightly engage each or both of the said staff sections. The centrally enlarged or bulging portion of the slide 20 is formed with the lower notch 22 of the umbrella and pivotally connected between the depressions of the said notch are the inner and shorter members 23 of the sectional braces 24. The outer sections 25 of the braces 24 are hingedly connected with the sections 23 through the medium of rule joints 26. By this arrangement the sections may be broken in only one direction and 30 that toward the staff of the umbrella. The outer extremities of the sections 25 are pivotally connected to the inner rib member 16 through the medium of hinge joints 27. Each of the hinge joints 27 is formed of a single strip of suitable material, the same comprising a substantially U-shaped body portion which is adapted to overlie the cross sectional U-shaped member 16. The inner or free edges of the member 27 are each bent 35 inwardly to provide what may be termed ways 28, the same adapted to engage the inner sides and edges of the cross sectional U-shaped member 16.

The numeral 29 designates the removable tip of the umbrella. This tip has its lower extremity constructed of some suitable flexible material, the same being slitted so as to be effectively sustained within the open

mouth of the staff section 2. In most cases it has been found desirable to provide the tip 29 with a flexible element 30, the latter being secured in any desired manner within the hollow staff section 2. The tip 29 is also provided with a suitable cap piece 31, the latter adapted to shield the upper portion of the covering which is connected to the ribs adjacent the top notch 15 of the device.

When it is desired to collapse the frame to the position illustrated in Fig. 2, the section 3 is first telescoped within the handle 4 as previously described. The spring catch 13 is pressed within the hollow staff section to allow the said section to collapse within the section 3. The sections 23 and 25 of the brace 24 are broken at their hinges 26 and the slide is forced upwardly until after the same has passed the spring catch 14 which contacts and sustains the lower edge thereof. The outer rib sections 19 are then 70 folded as illustrated in the said Fig. 2 of the drawings and the covering, not shown, is received within the space between the rib sections 16 and 19.

Having thus fully described the invention, 75 what I claim as new, is:—

A folding umbrella comprising a plurality of telescopic sections, each decreasing in diameter and provided with ribs and braces for said ribs, of a slide constructed from a single piece of resilient material having an enlarged central portion spaced from said sections and converging opposite end portions slit through their length and normally disposed in contacting engagement with said sections, and apertured lugs formed integrally with said central portion and adapted to connect the braces of said ribs for the purpose specified.

In testimony whereof I affix my signature 90 in presence of two witness .

ALBERT WEBER.
